HOLDER FOR WRITING INSTRUMENTS

Filed Dec. 22, 1930

INVENTOR.
John W. Fitzgerald
BY
Ira Milton Jones
ATTORNEY.

UNITED STATES PATENT OFFICE

JOHN W. FITZ GERALD, OF MILWAUKEE, WISCONSIN, ASSIGNOR TO BRIGGS AND STRATTON CORPORATION, OF MILWAUKEE, WISCONSIN, A CORPORATION OF WISCONSIN

HOLDER FOR WRITING INSTRUMENTS

Application filed December 22, 1930. Serial No. 504,042.

This invention relates to certain new and useful improvements in holders for pens, pencils and the like having a receptacle into which the inner end of the pen, pencil or the like is adapted to be inserted, and means for mounting the receptacle whereby the same may be swiveled to any desired position; and has as an object the provision of an improved mounting for the receptacle whereby the same may be readily detachably secured to any surface such as a desk top or the like.

A more specific object of this invention resides in the provision of an improved holder of the character described adapted to be attached to any supporting surface such as a desk top or the like by vacuum means.

And a further object of this invention resides in the provision of a holder of the character described comprising an elastic vacuum cup member, means swivelly connecting the pen, pencil or the like receptacle with the cup, and a shield positioned over the cup to conceal the same and provide a neat external appearance for the device.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a view partly in section and partly in elevation, of a pen or other writing instrument holder embodying my invention;

Figure 2 is an enlarged view partly in section and partly in elevation taken through Figure 1 on the plane of the line 2-2; and

Figure 3 is a perspective view illustrating the various elements of my improved holder separated and in their relative positions of assembly.

Referring now more particularly to the accompanying drawing in which like numerals designate like parts, 5 designates a vacuum cup member constructed, in the present instance of rubber, and having the headed end 55 of a stud 7 embedded therein. A stem 8 is threaded on the exposed end of the stud 7 and the outer end of the stem is internally threaded to receive a stud 9 of a ball member 10 having a slot or groove 11 therein for the 60 reception of a disc like member 12 carried by the inner closed end 13 of a receptacle 14. The disc 12 is pivotally mounted in the slot or groove 11 of the ball 10 by a pivot pin 15. The receptacle 14 is of conventional construction having a longitudinally extending bore 65 into which the writing end 16 of a pen, pencil or the like 17 is inserted.

As will be obvious, the assembly described is mounted on a suitable supporting surface 70 such as a desk top or the like by placing the cup 5 thereon and exerting pressure on the same by bearing on the ball member 10 so as to depress the medial portion of the cup and expel the air from underneath its dished 75 surface 18, the vacuum thus formed firmly maintaining the cup in position. The pivot pin 15 permits the receptacle 14 with the pen therein to be moved vertically as will be readily apparent and if desired, the mounting of 80 the stud 7 within the cup 5 may be such that the receptacle may be swung about the vertical axis of the stud or the stem 8 may be so constructed as to accommodate this movement.

In order to give a finished or dressed appearance to the device, a semi-spherical shell 19, is disposed over the cup 5 and has a collar or sleeve 20 extended therefrom of a diameter to slidably receive the stem 8, the sleeve or 90 collar 20 passing into a cap 21 carried by the upper end of the stem 8 in the manner illustrated in Figure 2.

If desired, a light spring 22 may be confined between the upper end of the collar 20 95 and the cap 21 so as to yieldably retain the marginal edge of the semi-spherical shell 19 in engagement with the supporting surface on which the cup 5 is mounted.

In Figure 2, the dotted lines indicate the 100

position of the parts with reference to the supporting surface prior to the application of pressure thereon to expel the air from the chamber formed by the dished undersurface 5 of the cup 5, and the full lines illustrate the position of the parts with the device attached to the supporting surface.

What I claim as my invention is:

- 10 1. In a holder for writing instruments, a mounting element comprising a stem and a suction cup adapted for engagement with a supporting surface, a receptacle adapted to receive a writing instrument and carried by the stem, a casing movably mounted on said stem and adapted to have its marginal edge engaged with the supporting surface to enclose the suction cup, and means yieldably maintaining the casing marginal edge in engagement with the supporting surface.
- 15 2. In a holder for writing instruments, a mounting element comprising a stem and a suction cup adapted for engagement with a supporting surface, a receptacle adapted to receive a writing instrument and carried by the stem, a casing movably mounted on said stem and adapted to have its marginal edge engaged with the supporting surface to enclose the suction cup, and means confined between a portion of the casing and a 20 portion of the mounting stem for yieldably maintaining said marginal edge of the casing in engagement with the supporting surface to thereby impose an upward tension on the mounting stem.
- 25 3. In testimony whereof I have hereunto affixed my signature.

JOHN W. FITZ GERALD.
